CLAIM

The ornamental design for a shoe with translucent heel element, as shown and described.

DESCRIPTION

FIG. 1 is a first rear perspective view of a shoe with translucent heel element showing my new design;

FIG. 2 is a rear view thereof; and,

FIG. 3 is a second rear perspective view thereof.

The broken lines immediately adjacent to the bottom and sides of the shaded area represent unclaimed boundaries of the design. The broken lines showing an insole member form no part of the claimed design. The broken lines showing the remainder of the shoe are for environmental purposes only and form no part of the claimed design.
